DESIGN FOR A COMBINED CUFF PROTECTOR AND ERASING SHIELD

Meyer Cohen, Flushing, N. Y.

Application March 2, 1945, Serial No. 118,226

Term of patent 7 years

(CL D74—1)

To all whom it may concern:

Be it known that I, Meyer Cohen, a citizen of the United States, residing at Flushing, in the county of Queens and State of New York, have invented a new, original, and ornamental Design for a Combined Cuff Protector and Erasing Shield, of which the following is a specification, reference being had to the accompanying drawing, forming part thereof.

I claim:

The ornamental design for a combined cuff protector and erasing shield, as shown.

MEYER COHEN.
